UNITED STATES PATENT OFFICE

2,547,345

APPARATUS FOR ATTACHING AND
DETACHING MACHINE PARTSEdwin E. Skilling, Chula Vista, Calif., assignor to
International Tool Corporation, Chula Vista,
Calif.

Application August 16, 1948, Serial No. 44,506

5 Claims. (Cl. 29—252)

1

This invention relates to and has for a main object the provision of an apparatus for attaching and detaching machine parts through controlled application of pneumatic or hydraulic pressure or a combination thereof, and for moving a part on and while it is tightly fixed to its support.

Such an apparatus is particularly adapted for attaching sleeves or bushings to bodies, gears to shafts, wheels to axles, arbors to their supports, and in turn for detaching or removing such elements from attached positions, respectively, as well as for applying power to elements in other ways and for various purposes.

This invention contemplates the provision of means for hydraulically operating a portable unit for application to a piece of work remotely located relative to a source of power.

Another object is to provide a unit in which the cylinder and ram of a hydraulic unit are arranged to receive suitable attachments adapted to engage portions of fixed bodies and portions of parts to be moved on their bodies when power is applied to the ram by displacement of a fluid contained in said cylinder.

It is desirable to provide a master unit including a cylinder of large area with a plunger therein operable in a given direction by a fluid under pressure, a hydraulic cylinder adjacent said large cylinder and adapted to contain a fluid which is displaceable as by means of a piston fixedly attached to said plunger for exhausting fluid from the associated cylinder and transferring the fluid to the secondary unit, through flexible connections between the reservoir cylinder and the cylinder of the secondary unit for applying power to the secondary unit.

An object also is to provide means for urging the master plunger and the piston of the reservoir cylinder in an opposite direction to that of a power stroke upon cessation or sufficient reduction of pressure thereto for at times restoring the master unit to normally inoperative position and in readiness for a succeeding operation.

Other objects and advantages of our apparatus will appear as the description thereof progresses.

A preferred comprehensive form of apparatus is shown in the accompanying drawings, subject to modification, within the scope of the appended claims, without departing from the spirit of the invention. In said drawings:

Fig. 1 is an elevational view of a master unit, partly in section and of the same general character as that shown in my copending application, Serial No. 44,507, filed August 16, 1948;

2

Figs. 2 and 3 are, respectively, horizontal sections on lines 2—2 and 3—3 of Fig. 1;

Figs. 4 and 5 are, respectively, elevational views, partly in section, of a secondary unit arranged to receive power from the master unit as when removing a sleeve from a body and with the ram in different positions in its cylinder as at the inception and partial removal stage of a sleeve;

Fig. 6 is a transverse sectional view of a special attachment adapted to apply power to and remove a sleeve from its supporting body as the elements (ram or cylinder) are relatively moved;

Fig. 7 is an elevational view of the secondary unit specially fitted with attachments for inserting a sleeve in a supporting body and partly in section;

Figs. 8 and 9 are sectional views on lines 8—8 and 9—9, respectively, of Fig. 7;

Fig. 10 is a perspective view of a stirrup attachable to the ram of Fig. 7;

Fig. 11 is a perspective view of a special fixture applicable to the secondary unit for effecting insertion of a sleeve.

Briefly described, the apparatus herein disclosed includes a master power unit M, a secondary power unit S, and an intermediate hydraulic unit I between the master and secondary units.

Master unit M includes a base B mounted on wheels B₁, a large upright cylinder C held on base B as by means of stay bolts I fixed at their bottoms to the base and at their tops to a head C₁ forming a top closure for said cylinder.

A plunger D is slidably mounted in cylinder C and forms a closure for the bottom of the case while providing separate chambers 2 and 3 on opposite sides thereof. Chamber 2 is vented to the atmosphere at 4 through head C₁ while chamber 3 is sealed against air except through an inlet 5 through which compressed air from an adequate source is admitted for application to plunger D for effecting a power stroke of the plunger.

Said plunger has a tubular stem D₁ which extends upwardly into a coaxial intermediate cylinder I which is attached to head C₁ as shown in Fig. 1. Stem D₁ carries a piston D₂ which slides in and closely fits the interior of cylinder I. Stem D₁ is tensioned as by means of a compression spring D₃ and a tension spring D₄ which are telescopically arranged in the stem and have their upper extremities connected at 6 while the lower end of spring D₄ is fixed at 7 to base B and the lower end of spring D₃ is held against a split

retainer ring d' held in an internal groove in the bottom of stem D_1 , as shown in Fig. 1.

Thus, as plunger D moves upwardly under air pressure spring D_4 is gradually extended until it attains an uppermost position and maximum capacity while the spring D_3 is compressed, thereby preventing overloading of spring D_4 and by combining the power of the two springs provides for application of maximum effort to the plunger D at and following institution of a downstroke of the plunger, and yet providing sufficient effort to move said plunger to the end of its downward stroke.

Cylinder I has a head closure I' which has a nipple 8 threaded into the upper end of the cylinder and in which there is a bore 9 in communication with and for filling cylinder I with a suitable fluid. Said head has an outlet 10 for receiving a fixture 11 of a flexible hose 12 which conducts fluid from cylinder I to secondary unit S , as hereinafter described.

Unit S as best shown in detail in Fig. 4, includes a cylinder S_1 which is closed at one end (upper end as shown) by a head S_2 affixed as by welding at 13 , a ram S_3 having a stem S_4 slideable in cylinder S_1 and a ring S_5 threaded into the other end of the cylinder and bored to form a guide for stem S_4 .

In the form of apparatus shown in Fig. 4, the parts of which are so formed and arranged as to quickly remove cylindrical parts such as liners, sleeves, bushings, etc., from their supporting bodies, cylinder S_1 is rigged with a cylindrical removing fixture S_6 and ram stem S_4 is fitted with an attachment S_7 particularly adaptable for bearing against a crank pin E of an internal combustion motor when the pin is in its downmost position in order that the lower end 14 of a sleeve F may be engaged by gripping devices carried by head S_6 and the sleeve moved upwardly and out of its bore as pressure is applied to the top of ram S_3 .

To such end head S_6 includes a cylindrical body bored and internally threaded at 15 for attachment to a reduced externally threaded end portion 16 of cylinder S_1 and counterbored at 17 to neatly fit the outer surface of said cylinder. Thus, when head S_6 is affixed by cylinder S_1 a shoulder 18 on said head will abut a companion shoulder on the cylinder and thereby limit the thrust of the head on the cylinder. A circular sleeve 19 is telescopically slideable on the body S_6 and is formed with an annular internal flange 20 at its top adapted to slide on a reduced portion 21 of the body between a shoulder 22 and a split retaining ring 23 held by tension in an annular groove 24 , as in Fig. 4.

Sleeve 19 has its depending skirt slotted as at 25 in Fig. 6 for providing a plurality of longitudinal tensioned fingers 26 which are fulcrumed at their junctions with flange 20 while their free ends depend therefrom and are formed with shoulder 27 adapted at times to underlie the lower end of sleeve F .

Head S_6 is formed with a frusto-conical flange 28 which, when the head S_6 and sleeve 19 are relatively moved, will expand and permit the contraction of fingers 26 into and from positions of engagement with sleeve F , respectively, depending upon a particular direction of movement of one element relative to the other.

In the position shown in Fig. 4, if the head S_6 is moved upwardly or the sleeve 19 moved downwardly the fingers 26 will expand outwardly until their shoulders 27 are disposed below sleeve

F and a subsequent movement upwardly of the body and sleeve 19 would be effective for moving sleeve F upwardly in its supporting body G when power is applied to ram S_3 . In such operation the foot S_7 engages and bears against crank pin E or any other fixed member while the cylinder S_1 and head S_6 move upwardly on the ram due to a build-up of pressure in chamber 29 between cylinder head S_2 and S_3 . Fluid under pressure is supplied from intermediate cylinder I under influence of plunger D and piston D_2 , through conduit or hose 12 and a fitting 30 attached to or formed on head S_2 .

The ram of Figs. 4 and 5 may be arranged similarly to stem D_1 of plunger D (Fig. 1) with telescoping springs S_9 and S_{10} having their lower ends connected at a while the upper end of spring S_{10} is anchored as by means of a pin a' to member 30 and the upper end of spring S_9 abuts a split retainer ring d' of ram S_3 . Thus, said springs are of the same influence on ram S_3 as the similarly arranged springs D_3 and D_4 are on plunger D , except that the springs of the ram are tensioned as the ram moves downwardly in its cylinder and tend to impart effort to the ram to effect its upward retractive stroke.

In Fig. 4, head fingers are shown as contracted and in readiness for expansion as in Fig. 5, in which case the sleeve F has been partially removed from its support G .

Ram stem S_4 is bored and threaded to receive a nipple 31 of foot S_7 while the body of the foot is wing-like and concave on its bottom surface, as shown.

As shown in Figs. 7 to 10, inclusive, the power application unit S is fitted with attachment differing from those of Fig. 4 for the purpose of inserting a sleeve F or other part into a receiving bore of a body as at G . In this form and arrangement the cylinder S_1 , ram S_3 , and ring S_5 are identical with corresponding elements of Fig. 4 but in lieu of the sleeve removing head S_6 I provide a sleeve inserting head S_8 of stirrup-like form with upstanding arcuate sides $32, 32$ adapted to overlie cylinder S_1 and a flat bottom 33 with a nipple 34 thereon for attachment to the socket at the lower end of ram stem S_4 to which the foot S_7 of Fig. 4 is attached. Sides 32 have flanges 35 at their upper ends adapted to engage and bear against the upper end of sleeve F when said sleeve is positioned as in Fig. 7 for insertion in a bore of body G .

A locking ring H is threadedly affixed to portion 16 of cylinder S_1 in lieu of the body of head S_6 and has pairs of spaced lugs $36-36, 36-36$, at diametrically opposite positions (Fig. 8) adapted to seat in selected pairs of notches $37-37$ formed in opposite edges of bores $38-38$ of a thrust rack S_9 which is employed in lieu of the attachment S_7 of Fig. 4. Rack S_9 carries a detachable or permanent foot 39 formed as a hook for underlying the crank pin E when in uppermost position so that when cylinder S_1 is locked to the rack through ring H and pressure is applied to ram S_3 said cylinder will be held against upward movement while the ram will descend in the cylinder and carry with it the head S_8 and through said head force the sleeve F into its bore in body G . Preferably, as shown in Fig. 9, a tooled ring 40 may be carried between sleeve F and flanges 35 of head S_8 and the lower surfaces of the flanges and the upper surface of ring 40 correspondingly bevelled.

It will be noted that the apparatus shown and described herein is not merely a fixed machine

arranged to support or operate upon a particular work during an operation, but the operating unit S is structurally an independent portable unit of light weight which is readily operative for various purposes on different types of work, thereby affording a power unit of general utility in a factory or shop.

The essence of the invention, therefore, is in the simplicity and efficiency of the power unit and in its novel structure, arrangement of elements, and special adapters by means of which many different operations may be effected through the employment of a single power unit.

Essentially then, the power application unit is of major importance in that it includes the cylinder and ram elements and requisite attachments selectively applicable thereto, whereby, when one of said elements is anchored or bears against a stationary work support while the other element of the combination engages the work, the power unit upon application of pressure thereto becomes effective for inserting a part in, removing the same from, or merely adjusting said part in or on its support.

I claim:

1. An apparatus for attaching and detaching parts from bodies and arranged for operative connection with the cylinder and plunger of a hydraulic ram comprising: a head formed with a stirrup having peripherally spaced arcuate sections and having a bottom underlying and affixed to the ram plunger and flanges at their upper ends and a thrust rack having parallel arms overlying and locked to said cylinder against longitudinal and rotary movement and provided with an anchor at its extended end for engagement with a stationary body, whereby when pressure is applied between the plunger and the adjacent end of the cylinder, the cylinder will be held stationary while the plunger and head move to occasion movement of the work in a body.

2. An apparatus for attaching and detaching parts from bodies and arranged for operative connection with the cylinder and plunger of a hydraulic ram comprising: a head formed with a stirrup having peripherally spaced arcuate sections and having a bottom underlying and affixed to the ram plunger and flanges at their upper ends and a thrust rack having parallel arms overlying and locked to said cylinder against longitudinal and rotary movement and provided with an anchor at its extended end for engagement with a stationary body, whereby when pressure is applied between the plunger and the adjacent end of the cylinder, the cylinder will be held stationary while the plunger and head move to occasion movement of the work in a body, said rack arms having notches therein, and a locking member affixed to the ram cylinder having portions complementary to and adapted to seat in selected notches for operatively holding the rack in position.

3. An apparatus for attaching and detaching parts from bodies and arranged for operative connection with the cylinder and plunger of a hydraulic ram comprising: a head formed with a stirrup having peripherally spaced arcuate sections and having a bottom underlying and affixed to the ram plunger and flanges at their upper

ends and a thrust rack having parallel arms overlying and locked to said cylinder against longitudinal and rotary movement and provided with an anchor at its extended end for engagement with a stationary body, whereby when pressure is applied between the plunger and the adjacent end of the cylinder, the cylinder will be held stationary while the plunger and head move to occasion movement of the work in a body, said rack arms being positional intermediate said arcuate head portions.

4. An apparatus for attaching and detaching parts from bodies and arranged for operative connection with the cylinder and plunger of a hydraulic ram comprising: a head formed with a stirrup having peripherally spaced arcuate sections and having a bottom underlying and affixed to the ram plunger and flanges at their upper ends and a thrust rack having parallel arms overlying and locked to said cylinder against longitudinal and rotary movement and provided with an anchor at its extended end for engagement with a stationary body, whereby when pressure is applied between the plunger and the adjacent end of the cylinder, the cylinder will be held stationary while the plunger and head move to occasion movement of the work in a body, the bottom of said stirrup having a threaded extension detachably secured to an end of the ram plunger.

5. An apparatus for attaching and detaching parts from bodies and arranged for operative connection with the cylinder and plunger of a hydraulic ram comprising: a head formed with a stirrup having peripherally spaced arcuate sections and having a bottom underlying and affixed to the ram plunger and flanges at their upper ends and a thrust rack having parallel arms overlying and locked to said cylinder against longitudinal and rotary movement and provided with an anchor at its extended end for engagement with a stationary body, whereby when pressure is applied between the plunger and the adjacent end of the cylinder, the cylinder will be held stationary while the plunger and head move to occasion movement of the work in a body, and an annular adaptor encompassing the ram cylinder and interposed between the work and the flanges of the arcuate sections of the head.
